ADJUSTABLE RAMP

Arthur R. Bennett, 4019 SW. 12th St.,
Plantation, Fla. 33314

Filed Nov. 5, 1970, Ser. No. 25,835

Term of patent 14 years

Int. Cl. D12—16

U.S. Cl. D41—1

FIG. 1

FIG. 2

FIG. 3

FIG. 4

FIG. 5

FIG. 1 is a top plan view of an adjustable ramp showing my new design;

FIG. 2 is a side elevational view of the adjustable ramp;

FIG. 3 is an end view of the adjustable ramp looking up the incline of the ramp;

FIG. 4 is an end view of the adjustable ramp looking at the adjustable legs thereof; and

FIG. 5 is a bottom plan view of the adjustable ramp.

I claim:

The ornamental design for the adjustable ramp as shown.
